UNITED STATES PATENT OFFICE.

EDWARD D. PRIEST, OF SCHENECTADY, NEW YORK, ASSIGNOR TO THE GENERAL ELECTRIC COMPANY, OF NEW YORK.

ELECTRIC RAILWAY-MOTOR.

SPECIFICATION forming part of Letters Patent No. 595,409, dated December 14, 1897.

Application filed February 23, 1897. Serial No. 624,566. (No model.)

To all whom it may concern:

Be it known that I, EDWARD D. PRIEST, a citizen of the United States, residing at Schenectady, in the county of Schenectady, State 5 of New York, have invented certain new and useful Improvements in Electric Railway-Motors, (Case No. 506,) of which the following is a specification.

The present invention relates to electric 10 railway-motors, and has for its object to improve their construction and to reduce the cost of maintenance.

In the accompanying drawings, attached to and made a part of this specification, Figure 15 1 is a side view of a motor. Fig. 2 is a sectional view taken on the line 2 2 of Fig. 1, and Fig. 3 is a cross-section of an armature-bearing.

The motor A is a four-pole machine, and 20 the field-magnet is divided into two substantially equal parts B and B'. The top half is supported at the rear end by bearings on the axle C and at the front end by the bar D. The latter is preferably spring-supported on 25 the car-truck. The lower half B' of the magnet-frame is secured to the upper half by bolts E E'. The armature F is provided with bearings, which are mounted in boxes G on 30 the lower half of the frame, and by removing the nuts from the bolts E E' the armature and lower half of the motor may be removed without disturbing the suspension of the upper half.

Instead of mounting the brasses for the armature-shaft F' directly upon the field-magnet in the usual manner boxes G, separable from and mounted in cut-away portions of 35 the field-magnet, are provided, in which the brasses are mounted. These boxes are substantially square, and each is provided with outwardly-extending lugs G' G², through 40 which extend bolts H for securing the box to the field-magnet casting. Extending upwardly from the lower part of the box and formed integral therewith is a projection I, forming a support and guide for the lower brass I'. A similar projection I² extends 45 downward from the top of the box and forms a support and guide for the upper brass I². The brasses, which partially surround the 50 shaft F', are adjusted in the supports I I² by

means of bolts J J', working in screw-threads, as shown, and having rounded ends, which enter sockets in the brasses. To prevent the bolts J J' from turning, the outer ends of the 55 lugs which support them are slotted, and cotter-pins extend through the bolts and engage therewith.

The arrangement of the bolts and brasses is such that a limited angular movement of 60 the brasses in a plane parallel to the armature-shaft is permitted, which is sufficient to compensate for inaccuracies in workmanship.

The lower armature-shaft brasses wear faster than the top ones, and at times one 65 brass wears faster than the corresponding one. With the ordinary construction this necessitates the use of shims, and to properly shim a bearing the bearing-cap has to be removed and the armature lifted to enable the 70 shim to be inserted in place, and often a number of trials are required before the bearing is adjusted to the proper position. By my arrangement the armature-brasses can readily be adjusted without unhanging the 75 motor from the truck or otherwise disturbing it. The bolts J J', being outside of the motor-frame, are readily accessible.

By providing a separate box for the armature-bearings the amount of necessary 80 machine-work in the field-magnet frame is reduced, and by making the supports for the lugs G' G² on the same line with the joint between the parts of the field-magnet they may be finished by the same tool and at the same 85 time with the joint. The box G being comparatively small it is easy to handle and the work thereon is facilitated.

Referring more particularly to the means for oiling the armature-shaft, the box G is 90 provided with two chambers K K', one on each side of the shaft and connected by a passage K². Covers P P' are provided for the chambers to permit the insertion of waste and oil. The chambers are preferably filled 95 with cotton-waste T, saturated with oil, and the waste by engaging with the sides of the armature-shaft keeps it well oiled. The rear end of the box is provided with a flange or lip L, closely encircling the oil-thrower M, 100 which is mounted on the armature-shaft F'. This is arranged to prevent the oil from work-

ing to the outside of the box and into the armature-winding and interior of the motor. As a further precaution a second oil-thrower M' is mounted on the shaft, and inclosing it 5 is a small auxiliary chamber O, connecting with the outside of the motor.

The construction of both armature-bearings is the same, the one on the right or gear end of the motor, Fig. 2, being longer than the commutator end bearing on account of the additional strain thereon.

The boxes G are shown as being supported from the lower half of the field, but they may be carried by the upper half, if desired.

15 What I claim as new, and desire to secure by Letters Patent of the United States, is—

1. In a dynamo-electric machine, the combination of an armature, a shaft therefor, a field-magnet inclosing the armature, boxes 20 mounted in cut-away portions of the field-magnet and separable therefrom, armature-shaft brasses mounted in boxes, and means for securing the boxes to the magnet-frame.

2. In an electric motor, the combination of 25 an armature, a shaft therefor, a field-magnet inclosing the armature, boxes separable from the field-magnet in which the armature-shaft is mounted in cut-away portions of the field-magnet and separable therefrom, armature-30 shaft brasses mounted in the boxes, and bolts for securing the boxes to the magnet.

3. In an electric motor, the combination of 35 an armature, a shaft therefor, a field-magnet inclosing the armature, boxes separable from and mounted in cut-away portions of the field-magnet, armature-shaft brasses mounted in the boxes, adjusting-bolts mounted in lugs integral with the boxes and situated above and below the brasses, and rounded ends on 40 the bolts fitting sockets in the brasses, as set forth.

4. In an electric railway-motor, the combination of a field-magnet centered on a car-45 axle, an armature mounted within the field-magnet, a shaft therefor, mounted in cut-away portions of the field-magnet, armature-shaft brasses mounted in the boxes, means for securing the boxes to the field-magnet, lugs within the boxes supporting and guiding 50 the brasses, bolts for adjusting the brasses, and lugs on the box in which the bolts are mounted.

5. In a dynamo-electric machine, the combination of an armature, a shaft therefor, armature-shaft brasses, boxes separable from 55

the field-magnet in which the brasses are mounted, chambers on both sides of the shaft adapted to be filled with oil and waste, and an auxiliary chamber or passage connecting with the exterior of the motor, for conveying 60 oil away from the armature.

6. In an electric motor, the combination of a field-magnet, an armature, a shaft therefor, armature-shaft brasses, boxes separable from the field-magnet in which the brasses are 65 mounted, chambers for oil and waste located on both sides of the shaft, an oil-thrower mounted on the armature-shaft, and an auxiliary chamber in close proximity to the oil-thrower, for receiving the oil therefrom and 70 conveying it to the outside of the motor.

7. In an electric motor, the combination of an armature, a shaft therefor, armature-shaft brasses, boxes separable from the field-magnet in which the brasses are mounted, the 75 brasses being situated above and below the shaft and partially surrounding it, chambers on both sides of the shaft filled with oil and waste, the waste engaging with the sides of the shaft, an oil-thrower mounted on the armature-shaft for conveying oil from the shaft to the chambers, an auxiliary chamber connecting with the exterior of the motor, and a second oil-thrower arranged in proximity to the first for conveying oil to the auxiliary 85 chamber.

8. As an article of manufacture, a bearing-box having projections formed integral therewith and located at the top and bottom of the box for supporting and guiding the bearing-brasses, lugs on the outside of the box for supporting it, closed chambers on both sides of the projections connected by a passage, and an auxiliary chamber connected with the outside of the box for carrying away oil. 90

9. In an electric motor, the combination of a field-magnet, an armature, a shaft therefor, brasses mounted above and below the shaft and partially encircling it, supports and guides for the brasses, means for adjusting 100 the brasses, chambers on both sides of the shaft, and waste in the chambers engaging with the sides of the shaft.

In witness whereof I have hereunto set my hand this 19th day of February, 1897.

EDWARD D. PRIEST.
